UNITED STATES PATENT OFFICE

JAMES B. CROCKETT, OF CAMBRIDGE, MASSACHUSETTS, ASSIGNOR TO CAMBRIDGE RUBBER COMPANY, OF CAMBRIDGE, MASSACHUSETTS, A CORPORATION OF MASSACHUSETTS

ARTIFICIAL FLOWER AND METHOD OF MAKING SAME

Application filed February 13, 1928. Serial No. 253,797.

This invention relates to improved artificial flowers and to improved methods of manufacture of the same. Specifically it relates to artificial flowers made largely from 5 rubber or rubber compounds.

It is well understood that artificial flowers made wholly or in part from commercial rubber are old, but as in any art that involves the manufacture of an article intended to simulate a natural thing, a multiplicity of problems arise in attempting to obtain a perfect or substantially perfect representation of the natural product. In the production of artificial flowers from more or less standard 10 forms of manufactured rubber available in the market, it has been particularly difficult to produce an article which develops and retains the graceful and natural formations corresponding to that of natural flowers, and 15 to secure the delicate color tints and blendings which are present in the natural flower and without which no real imitation is obtained.

Furthermore, the production of rubber parts in various forms for artificial flowers, 20 for instance, by moulding under pressure and vulcanizing at high temperatures, requires the use of expensive and heavy machinery, moulds and equipment, and produces poor results, having in mind the special purposes 25 and effects desired.

Heretofore no suggestions have been made aimed particularly to produce good imitations of natural flowers in rubber by inexpensive methods, such methods as would be practical to be carried out, for instance, by those 30 now engaged in the manufacture of artificial flowers from other materials.

This invention therefore has for one of its objects to produce an improved imitation 35 flower by relatively inexpensive methods and it is mainly directed to the formation of the stem and calyx of an artificial flower by assembling elements into a form and dipping same one or more times into a rubber solution, thereby coating the assembly with rubber. The form is then withdrawn from the 40 solution and the rubber coating dried and vulcanized according to ordinary methods. Reference is made to my co-pending applications Serial No. 242,526, filed December 24,

1927, and Serial No. 253,798, filed February 13, 1928, for other improved methods of manufacture.

In the drawings:

Fig. 1 is an elevation of an artificial flower 55 such as is produced by my new method.

Fig. 2 is an elevation of the calyx and part of the stem of the flower shown in Fig. 1.

Fig. 3 is an elevation partly in section of 60 the form on which the calyx is produced.

Fig. 4 is an elevation partly in section of the rubber tube hereinafter referred to which forms part of the stem of the flower shown in Fig. 1.

Fig. 5 is an elevation of the wire herein- 65 after referred to.

Fig. 6 is an assembly of the parts shown in Figs. 3, 4 and 5, the assembly being shown as it appears after one or more dipping operations with a film of latex rubber deposited on 70 the assembled forms.

Fig. 7 is an elevation partly in section of the partially formed calyx and stem after removal of the form parts shown in Figs. 3 and 5. 75

According to a preferred method of carrying out this invention, a piece of rubber tubing 1 or tubing of any composition or material having the required rigidity and thickness is fitted over a wire 2. A calyx form 3 of 80 wood, porcelain, metal or other suitable material is also fitted over the wire 2 to abut one end of the tube 1, Fig. 6. This assembly constitutes a form for producing the stem 4 and calyx 5 of the flower. The assembly is then 85 dipped in a solution of rubber in an organic solvent, which solution may be colored by any of various pigments or dyes and may have incorporated therein various fillers and/or vulcanizing agents. When dipped and removed the form will be provided with a complete coating of rubber 6 which is dried and the operation repeated so often as desired when it is then finally dried and vulcanized.

After the vulcanizing operation, the calyx 95 form 3 may be removed leaving an extension of the wire 2 which may be used for securing the petals 7 or center of the flower within the calyx 5 formed by the rubber coating, or in some cases it may be desirable to withdraw 100

the wire 2 and insert a wire to which the bud or flower has already been attached. Under certain conditions, it may be desirable to use a calyx formed of rubber which is left in whole or in part with the assembly. The upper part of the calyx formed by the rubber coating may be cut in the form of points or petals 5^a to provide an exact reproduction of the calyx of the particular flower to be represented.

In some instances, it may be desirable to produce the calyx with a color-tone or tint which varies from that of the stem. This is easily accomplished by the present method 15 by dipping the entire form into a solution of one color and subsequently dipping a portion of the assembly into a solution of another color. It is also possible to color the entire flower, that is, with petals and leaves 20 attached, by dipping into variously colored baths after the calyx form has been removed and the petals and leaves attached.

By the above described method, a flower is formed which has a stem and calyx without 25 any exterior visible line of union between them. Both are extremely natural in appearance and the color scheme may exactly reflect that of the natural flower. The stem 4 has the necessary characteristic of rigidity 30 due to the rubber coated tube reinforced by wire in the center, and the bud or petals 6 of the flower are bound to the stem and calyx by the wire. If desired to further perfect this arrangement, the wire may be given an 35 adhesive coating before introduction to the rubber tube, so that it will be secured against rotative or longitudinal movement therein when the assembly has been perfected.

Having described the invention, what I 40 claim as new is:

1. The method of making artificial flowers or the like which consists of constructing a form by sliding a rubber tube over a wire and also sliding a calyx form element of 45 larger diameter than the rubber tube over said wire, dipping the assembly in a rubber solution causing it to be coated with rubber, removing the assembly from the rubber solution, drying, repeating the dipping operation until the coating is the desired thickness, vulcanizing and removing the calyx 50 part of the form from the assembly.

2. The method of making an artificial flower which consists of constructing a stalk 55 form having an enlarged part corresponding to the calyx, dipping said form into a solution of rubber, removing the form from the solution, drying, repeating the dipping operation until the coating is the desired 60 thickness, vulcanizing, removing the calyx part of the form from the assembly, and cutting the formed rubber calyx in points or the like to simulate a natural flower.

3. The method of making an artificial 65 flower which consists of constructing a stalk

form having an enlarged part corresponding to the calyx, dipping said form into a solution of rubber containing coloring matter, removing the form from the solution, drying, repeating the dipping operation until the coating is the desired thickness, vulcanizing, removing the calyx part of the form from the assembly and cutting the formed rubber calyx in points or the like to simulate a natural flower.

4. An artificial flower having a rubber tube for its stem portion, said tube being coated with a layer or film of rubber which extends upwardly beyond the rubber tube and forms the calyx of the flower.

5. An artificial flower having a rubber tube as its stem portion, said tube being provided with an exterior coating of rubber which extends upwardly beyond the tube and forms the calyx of the flower, the coated tube being reinforced by a wire.

6. An artificial flower comprising a wire, a rubber tube positioned around said wire, a coating of rubber around said rubber tube extending upwardly beyond said tube to form the calyx of the flower, said extended portion being cut to simulate the natural shape of the calyx, and petals, or the like, arranged within said calyx and secured by said wire.
